ADJUSTABLE CHOKE ATTACHMENT FOR
SHOTGUNS

Arlo E. Schroeder, Newton, Kans., assignor to
Flex-Prop Corporation, Inc., Marion, Kans., a
corporation of Kansas

Application May 1, 1953, Serial No. 352,399

4 Claims. (Cl. 42—79)

1

This invention relates to choke attachments for shotguns and more particularly to a variable choke attachment which is automatically adjusted in response to successive shots from the associated gun.

It is among the objects of the invention to provide an improved shotgun attachment which can be easily mounted on the muzzle end of a shotgun barrel and will vary the choke of the barrel from the original form or condition to a full choke condition; which is adjustable to intermediate choke conditions between a no-choke and a full-choke condition; which may be automatically adjusted from its no-choke condition to conditions of successively increasing choke by successive pulls on the gun trigger and may be similarly adjusted by other manually operated means without pulling the trigger; which can be connected to and disconnected from the gun trigger at will; which is effective on a gun barrel which actuates the breech mechanism of the gun by recoil of the barrel and does not interfere in any way with the operation of such a barrel; which does not interfere with the aiming or sighting of the associated gun; and which is simple and durable in construction, economical to manufacture, easy to install, and positive and effective in operation.

Other objects and advantages will become apparent from a consideration of the following description and the appended claims in conjunction with the accompanying drawings wherein:

Figure 1 is a fragmentary side elevational view of a shotgun with a choke varying attachment illustrative of the invention operatively mounted thereon;

Figure 2 is a fragmentary cross sectional view on an enlarged scale on the line 2—2 of Figure 1;

Figure 3 is a side elevational view of the portion of the mechanism illustrated in Figure 2;

Figure 4 is a perspective view on an enlarged scale of the mechanism illustrated in Figures 2 and 3;

Figure 5 is a transverse cross sectional view on the line 5—5 of Figure 1;

Figure 6 is a fragmentary longitudinal cross sectional view on the line 6—6 of Figure 5;

Figure 7 is a fragmentary cross sectional view similar to Figure 6 showing structural details of the mechanism illustrated in Figure 6; and

Figure 8 is an exploded perspective view of the portion of the mechanism illustrated in Figure 6.

With continued reference to the drawings, the shotgun fragmentarily illustrated in Figures 1 and 6 comprises a gun stock having a grip portion 10 at the front end of the stock, a forearm 11

2

extending forwardly from the grip portion 10, a barrel 12 bedded in the normally upper surface of the forearm 11, a receiver 13 mounted on the forearm at the rear end of the barrel and containing the breech mechanism of the gun, a trigger guard 14 mounted on and depending from the forearm at the end of the forearm adjacent the grip 10, and a trigger 15 pivotally mounted in the breech mechanism of the gun and depending through an opening 16 in the forearm into the trigger guard 14.

As the shotgun may be of a construction well known to the art, a further illustration and description thereof is considered unnecessary for the purposes of the present disclosure.

The gun barrel 12 is externally screw threaded near its muzzle end, as indicated at 18, and a sleeve structure, generally indicated at 20, receives the muzzle end portion of the gun barrel 12 and is threaded onto the screw threads 18 on the gun barrel. This sleeve 20 includes an intermediate portion 21 of cylindrical shape which closely receives the muzzle end portion of the gun barrel and is provided with internal screw threads 19 on the gun barrel and at its front end with an annular shoulder 22 of a width equal to the thickness of the gun barrel at the muzzle end of the latter which shoulder overlies and bears against the muzzle end of the barrel. The sleeve 20 further includes a rear portion 23 of partly conical shape having a bore which closely receives the corresponding portion of the gun barrel and having its thicker end at the rear end of the intermediate portion 21 and providing an external annular shoulder 24 extending entirely around the sleeve. The rear portion 23 of the sleeve tapers from the shoulder 24 to a featheredge at the rear end of the sleeve, so that the rear end of the sleeve is brought down substantially to the outer surface of the associated gun barrel. The sleeve 20 also includes a forward portion 25 of cylindrical shape extending forwardly from the shoulder 22 coaxially of the intermediate portion 21 and provided with longitudinally extending slots 26 equally spaced around the sleeve portion and dividing the sleeve portion into a plurality of longitudinally extending spring fingers 27. Each of the spring fingers 27 is provided on its outer surface with a ramp, as indicated at 28, which ramps extend longitudinally of the corresponding fingers medially of the width thereof and are provided with transversely concave outer surfaces and taper in thickness from their front ends located near the front ends of the corresponding

fingers to their rear ends located near the shoulder 22. A housing 30 of cylindrical shape circumspatially surrounds the sleeve 21 from the shoulder 24 to the front end of the front portion 25 of the sleeve and is provided at its rear end with a thickened annular portion 31 provided with internal screw threads which engage with external screw threads 32 on the sleeve 21 adjacent the shoulder 24 to secure the housing on the sleeve. At its front end the housing is co-terminous with the front end of the sleeve, and an annular plate or washer 33 is mounted on the front end of the sleeve portion 25 and within the front end of the housing 30 and closes the annular space between the housing and the sleeve, this end plate being rigidly secured to the housing, but being free of the sleeve, so that the front ends of the spring fingers 27 of the sleeve can move inwardly and outwardly relative to the inner edge of the annular end plate 33.

A plunger, generally indicated at 35, is slidably mounted on the front and intermediate portions of the sleeve 20 and comprises end rings 36 and 37 of rectangular cross sectional shape disposed in coaxial and spaced apart and substantially parallel relationship to each other, and struts 38 of flattened shape extending between and secured at their opposite ends to the rings 36 and 37 to hold the rings in position relative to each other, these struts being disposed in spaced apart and substantially parallel relationship to each other and being spaced at substantially equal angular intervals around the end rings. Both of the end rings 36 and 37 have substantially the same outside diameter, but the front end ring 36 has an inside diameter less than the inside diameter of the end ring 37 and it will be noted that the front end portion 25 of the sleeve 20 is of reduced diameter relative to the intermediate portion 21 and is joined at its rear end to the front end of the intermediate portion by a beveled annular shoulder 39.

When the plunger 35 is slidably mounted on the sleeve 20, it is disposed in the annular space between the sleeve 20 and the housing 30 with the front ring 26 closely encircling the outer surface of the front portion 25 of the sleeve 20, and the rear ring 37 closely encircling the outer surface of the intermediate portion 21 of the sleeve. The front ring 36 is provided at substantially equal angular intervals around the inner surface thereof with recesses and bearing balls 40 of hardened material are mounted one in each of the recesses in the front ring 36 and each ball rides in the grooved outer surface of a corresponding ramp 28 on the front sleeve portion 25, and a compression spring 42 surrounds the intermediate portion 21 of the sleeve between an internal annular shoulder 43 near the rear end of the housing 30 and the rear ring 37 of the plunger 35 and resiliently urges the plunger in a forward direction to move the front ring 36 of the plunger outwardly of the front portion 25 of the sleeve and the bearing balls 40 outwardly along the corresponding ramps 28 to move the spring fingers 27 toward each other and contract the front end portion of the sleeve portion 25 to thereby increase the choke at the muzzle end of the gun.

The housing 30 is provided in its under side with an opening 45 registering with the outer surface of the bottom strut 38' of the plunger 35 and the strut 38' is provided with notches 46 and 47 spaced apart therealong, each of the notches having an abrupt rear end disposed sub-

stantially radially of the plunger and having a forwardly and outwardly inclined surface extending from the inner limit of the rear end surface thereof.

A latch 48 of somewhat triangular shape is pivotally mounted at its forward, apical end on the housing 30 at the front end of the opening 45 in the housing and has its rear corner 49 disposed inwardly of the choke varying assembly 10 shaped to engage in the notches 46 and 47 in the plunger strut 38' to releasably hold the plunger at selected positions of adjustment longitudinally of the sleeve 20. A cover 50 attached to the housing 30 covers the opening 45 in the housing and the sear 48 and a spring 51 connected between this cover and the sear resiliently urges the sear to its notch engaging position, as illustrated in Figures 6 and 7.

The latch 48 is provided with a recess 53 opening to the outer side and to the rear, base end thereof, and with inclined longitudinally curved slots, as indicated at 54, in the walls thereof at the opposite sides of the recess 53, the slots being in registry with each other transversely 25 of the sear.

A bell crank lever 55 is pivotally mounted at its angle on a pivot pin 56 mounted in the cover 50 and having one leg 57 extending outwardly from the pivot pin 56 and its other leg 58 extending forwardly from the pivot pin and entering the recess 53 in the rear end of the latch 48. The pivotal connections between the latch 48 and the lever 55 have their axes substantially in parallel planes disposed perpendicular to the longitudinal center line of the gun barrel 12 and the choke sleeve 20.

A spring 60 connected between the lever 55 and the housing 30 at the rear of the opening 45 in the housing resiliently urges the lever 55 about 40 its pivot pin 56 in a direction to move the distal end of the outwardly extending leg 57 of the lever forwardly and the distal end of the forwardly extending leg 58 of the lever inwardly of the associated mechanism.

An abutment pin 61 extends transversely through the latch 48 and is received at its ends in the slots 51 in the sear and a spring 62 connected between this abutment pin and the sear resiliently urges the pin 61 to a position at the outer ends of the slots 51, as illustrated in Figure 7.

A pull cord 64 is pivotally connected at its front end to the lever 55 at the distal end of the lever leg 56 and extends from the lever 55 rearwardly along the gun barrel 12 and forearm 11.

The housing 30 is provided with a pair of closed slots 64' extending longitudinally of the housing at substantially diametrically opposite 60 locations therearound and each spaced approximately 90 degrees circumferentially of the housing from the housing opening 45. Cocking pins 65 and 66 extend one through each of the slots 64' and have reduced and externally screw threaded inner end portions threaded into tapped holes, as indicated at 67, in the rear ring 37 of the plunger in a manner such that the cocking pins project radially outwardly from the housing 30. The mechanism is cocked by moving the plunger 35 rearwardly by manual pressure on one or both of the cocking pins 65 and 66 until the latch 48 is engaged in the notch 46 nearest the front end of the plunger and the compression spring 42 is fully compressed. Under these 70 75

conditions, the split, front end portion 25 of the choke sleeve 21 is in a no-choke condition. With the choke mechanism cocked, as described above, a rearward pull on the pull cord 64 will pull the leg 57 of the lever 55 rearwardly, and the leg 58 of this lever outwardly against the abutment pin 61 and will move the sear 48 outwardly to release the sear from the notch 46 in the plunger strut 38'. The spring 42 will then move the plunger forwardly, and the engagement of the balls 40 with the ramps 28 will compress the choke portion 25 of the choke sleeve and increase the choke at the muzzle end of the gun barrel. As soon as the latch 48 has been moved outwardly to an extent such that it is released from the notch in the plunger strut 38', the distal end of the leg 58 of the lever 55 passes by the abutment pin 61 releasing the sear, so that the spring 51 swings the sear inwardly immediately and engages the sear with the next notch 47 in the plunger strut 38' to hold the plunger in an intermediate choke position. As soon as the rearward pulling force is released on the pull cord 64, the lever 55 is swung by the spring 60 to move the lever leg 57 forwardly and the lever leg 58 inwardly. When the distal end of the lever leg 58 strikes the abutment pin 61, this pin is moved along the slots 51 against the force of spring 62 until the lever leg 58 again passes the abutment pin, but in the opposite direction, whereupon the spring 62 returns the abutment pin to the outer ends of the slots 51 where it is again engaged by the lever leg 58 when a subsequent rearward pull is exerted on the pull cord 64. When the pull cord 64 is again pulled rearwardly, the sear is released from the notch 47, in the manner described above, and the spring 42 moves the plunger 35 forwardly to its full-choke position, the bearing balls 40 being then disposed near the thicker front ends of the corresponding ramps 28.

With this arrangement, the choke of the gun barrel is successively increased in a step by step manner, so that the range of the gun is increased and the scattering of the shot is reduced. This is of particular utility when a hunter is shooting at game, such as game birds, which fly rapidly away from the hunter, and it is desirable to increase the range of the gun for successive shots at the birds.

The forearm 11 of the gun is provided near the front end thereof with a recess 68 of elongated rectangular shape opening to one side of the forearm and the open side of this recess is covered by a cover plate 69 which extends marginally beyond the opening and is secured to the forearm by suitable means, such as the screws 70. A U-shaped bracket 71 is disposed in the recess 68 and has spaced apart and substantially parallel straight legs 72 and 73 which extend longitudinally of the forearm and of which the leg 72 is disposed against the inner side of the cover plate 69. Guide staples 75 and 76 are mounted on the plate 69 at the inner side of the plate and in spaced apart relationship longitudinally of the plate, and these staples slidably receive the bracket leg 72 and support the bracket in the recess 68 for a limited freedom of forward and rearward movement. The bight portion 76 of the bracket 71 is disposed substantially at right angles to the plate 69 and near the rear end of the recess 68, and a pull cord 78 is secured at its front end to the bight portion 77 centrally of this bight portion and extends rearwardly through a bore 79 in the forearm to a

connection at its rear end with the gun trigger 15, as indicated at 80, so that the bracket 71 will be pulled rearwardly each time the gun trigger 15 is pulled to fire the gun.

5 The cover plate 69 is provided with a substantially centrally located slot 81 extending longitudinally of the plate and a shaft 82 extends through this slot and is journaled in apertures provided in the legs 72 and 73 of the bracket 71. The shaft 82 is disposed substantially perpendicular to the plate 69 and a wing 83 extends laterally from the shaft 82 at the outer side of the plate 69 for use in applying manual pressure to turn the shaft. 10 A tubular sheath 85 extends along the gun barrel 12 and through a bore in the front portion of the forearm 11 from the rear end of the cover 59 to the front end of the recess 68 in the forearm, and the pull cord 64 extends slidably 15 through this sheath into the recess 68. A crank 86 projects laterally from the shaft 82 within the recess 68 and a longitudinally curved link 87 is pivotally connected at one end to the crank 86 and is connected at its other end to the rear end 20 of the pull cord 64, as indicated at 88. The link 87 extends across the shaft 82 and, when the shaft is in one rotational position, the link 87 holds the crank at this rotational position and connects the pull cord 64 to the bracket 71 in a 25 manner such that when the bracket is pulled rearwardly by the trigger connected pull cord 78, the pull cord 64 is also pulled rearwardly and operates the choke increasing mechanism at the muzzle end of the gun barrel in the manner fully described above. The shaft can be rotated by the wing 83 to a position in which the pull cord 64 is functionally released from the bracket 71, in which case the movement of the bracket 71 incident to gun firing 9995

setting providing a choke condition greater than the minimum choke condition of the assembly against the force of said spring means, flexible means connecting said latch means to said trigger for successively releasing said latch means upon successive gun firing movements of said trigger, and manually operated means mounted on said forearm and connected into said flexible means and effective to operatively disconnect said trigger from said latch means and to actuate said latch means independently of said trigger.

2. In combination with a shotgun having a forearm, a barrel bedded on said forearm and extending forwardly therefrom, and a trigger depending from said forearm near the breech end of said barrel, a choke bearing attachment mounted on the muzzle end of said barrel and including a choke sleeve receiving the muzzle end of said barrel and having a longitudinally split and circumferentially contractile portion extending forwardly from the muzzle end of said barrel, a plunger slidably receiving said choke sleeve, ramps disposed between said plunger and said longitudinally split sleeve portion effective to circumferentially contract said longitudinally split sleeve portion upon movement of said plunger longitudinally of said sleeve in one direction, spring means carried by said sleeve resiliently urging said plunger in said one direction, manually engageable means connected to said plunger for moving the latter in the other direction against the force of said spring means, latch means carried by said sleeve and effective to engage said plunger at spaced apart locations therealong and releasably hold said plunger at selected stages of its movement in said one direction from a no-choke to a full-choke position, and flexible means connecting said latch means to said trigger for releasing said latch means successively upon successive gun firing movements of said trigger.

3. In combination with a shotgun having a forearm, a barrel bedded on said forearm and extending forwardly therefrom, and a trigger depending from said forearm near the breech end of said barrel, a choke bearing attachment mounted on the muzzle end of said barrel and including a choke sleeve receiving the muzzle end of said barrel and having a longitudinally split and circumferentially contractile portion extending forwardly from the muzzle end of said barrel, a plunger slidably receiving said choke sleeve, ramps disposed between said plunger and said longitudinally split sleeve portion effective to circumferentially contract said longitudinally split sleeve portion upon movement of said plunger longitudinally of said

5 sleeve in one direction, spring means carried by said sleeve resiliently urging said plunger in said one direction, manually engageable means connected to said plunger for moving the latter in the other direction against the force of said spring means, latch means carried by said sleeve and effective to engage said plunger at spaced apart locations therealong and releasably hold said plunger at selected stages of its movement in said one direction from a no-choke to a full-choke position, flexible means connecting said latch means to said trigger for releasing said latch means successively upon successive gun firing movements of said trigger, and manually operated means connected into said flexible means and effective to functionally lengthen said flexible means to render said trigger ineffective to release said latch means.

4. In combination with a shotgun having a 20 forearm, a barrel bedded on said forearm and extending forwardly therefrom, and a trigger depending from said forearm near the breech end of said barrel, a choke bearing attachment mounted on the muzzle end of said barrel and including a choke sleeve receiving the muzzle end of said barrel and having a longitudinally split and circumferentially contractile portion extending forwardly from the muzzle end of said barrel, a plunger slidably receiving said choke sleeve, ramps disposed between said plunger and said longitudinally split sleeve portion effective to circumferentially contract said longitudinally split sleeve portion upon movement of said plunger longitudinally of said sleeve in one direction, spring means carried by said sleeve resiliently urging said plunger in said one direction, manually engageable means connected to said plunger for moving the latter in the other direction against the force of said spring means, 30 latch means carried by said sleeve and effective to engage said plunger at spaced apart locations therealong and releasably hold said plunger at selected stages of its movement in said one direction from a no-choke to a full-choke position, and flexible means connecting said latch means to said trigger for releasing said latch means successively upon successive gun firing movements of said trigger, said latch means being automatically disconnected from said trigger and 40 re-set immediately upon its release from said plunger to re-engage said plunger at a different location therealong and being reconnected to said trigger upon release of the trigger after a gun firing movement thereof.
